(57) **CLAIM**

The ornamental design for an insert for a footwear, boot, shoe, or the like, as shown and described.

DESCRIPTION

FIG. 1 is a perspective view of an insert for a footwear, boot, shoe, or the like showing the new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof;

FIG. 7 is a rear elevation view thereof; and,

FIG. 8 is another top plan view thereof, shown in the environment of a portion of a footwear, boot, shoe, or the like.

The broken lines illustrate portions of the insert for a footwear, boot, shoe, or the like that form no part of the claimed design.

1 Claim, 6 Drawing Sheets
